US00D694186S

(12) **United States Design Patent**
Terashita et al.

(10) **Patent No.:** US D694,186 S
(45) **Date of Patent:** ** Nov. 26, 2013

(54) **BRUSHLESS MOTOR**

(75) Inventors: **Shigeaki Terashita**, Kiryu (JP); **Yoji Unoki**, Kiryu (JP)

(73) Assignee: **Nidec Servo Corporation**, Gumma (JP)

(**) Term: **14 Years**

(21) Appl. No.: **29/386,029**

(22) Filed: **Feb. 24, 2011**

(30) **Foreign Application Priority Data**

Aug. 31, 2010 (JP) 2010-021046

(51) **LOC (9) Cl.** **13-01**

(52) **U.S. Cl.**

USPC **D13/112**

(58) **Field of Classification Search**

USPC D13/112, 113, 114, 120, 122, 199;
D15/3, 5, 199; 74/606 R, 609; 310/10,

(57) **CLAIM**

The ornamental design for a brushless motor, as shown and described.

DESCRIPTION

FIG. 1 is a front elevation view of a brushless motor according to our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a perspective view thereof.

The broken lines shown represent unclaimed subject matter and form no part of the claimed design.
